(57) **CLAIM**

The ornamental design for a sealing and vacuum-pumping device, as shown and described.

DESCRIPTION

FIG. 1 is a top, front, and left perspective view of a sealing and vacuum-pumping device showing our new design;

FIG. 2 is a front side view thereof;

FIG. 3 is a rear side view thereof;

FIG. 4 is a left side view thereof;

FIG. 5 is a right side view thereof;

FIG. 6 is a top plan view thereof; and,

FIG. 7 is a bottom plan view thereof.

Surface patterns of a nozzle in FIG. 5 depict unclaimed environmental subject matter.
